A. S. MEADOFF.
METALLIC SPRING MATTRESS.
APPLICATION FILED OCT. 12, 1917.

1,261,259.

Patented Apr. 2, 1918.

Inventor

ABRAHAM S. MEADOFF
By his Attorney

Chas. C. Gile

UNITED STATES PATENT OFFICE.

ABRAHAM S. MEADOFF, OF NEW YORK, N. Y.

METALLIC SPRING-MATTRESS.

1,261,259.

Specification of Letters Patent. Patented Apr. 2, 1918.

Application filed October 12, 1917. Serial No. 196,114.

To all whom it may concern:

Be it known that I, ABRAHAM S. MEADOFF, a citizen of the United States, and a resident of New York city, in the county of New York and State of New York, have invented 5 certain new and useful Improvements in Metallic Spring-Mattresses, of which the following is a specification.

The invention pertains to metallic spring 10 fabrics for use on bedsteads for supporting the usual hair or other soft mattress, and it consists in the novel features and structure hereinafter described, and particularly pointed out in the claims. The spring of 15 my invention comprises a main carrying frame of usual or any suitable type and a fabric composed of interengaging links of special outline connected by coiled springs with the end bars of said frame and at its 20 side edges with bars or stays which are connected at their ends by coiled springs with the aforesaid end bars, the structure as a whole being complete in itself and adapted to be handled as a unit and applied to or 25 removed from the customary bedstead. One of the essential objects of my invention is to provide a fabric whose links may be readily constructed and assembled and have an efficient yielding action due to their particular shape. Each link is approximately 30 of triangular outline, having an end portion formed with an eye and converging side members at whose ends are formed hooks, the hooks of one row of links being adapted 35 to engage the eyes of the adjacent row of links. The links are in parallel transverse rows and also in parallel longitudinal rows, and the fabric composed of the said links at its side edges is linked to appropriate 40 stay-rods or bars to add rigidity to the side edge portions of the fabric and which stay-rods or bars are yielding because of their connection by means of coiled springs with the end bars or members of the main carrying 45 frame.

The invention will be fully understood from the detailed description hereinafter presented, reference being had to the accompanying drawings, in which:

50 Figure 1 is a top view, partly broken away, of a spring constructed in accordance with and embodying the invention;

Fig. 2 is a corresponding view of one corner portion of the spring, shown as having 55 parallel stay-rods at its side edge in lieu

of the metal bar shown at the side edge of the fabric in Fig. 1;

Fig. 3 is a detached perspective view of one of the links of the fabric, and Fig. 4 illustrates a modified form of link for the 60 fabric.

The spring fabric of my invention is carried by a rigid frame ordinarily composed of end bars 10 and side bars 11, of suitable form and construction and well understood 65 in this art. An example of such frame is shown in my application for Letters Patent No. 40,810 filed July 19, 1915 as a renewal of my original application No. 819,318.

The fabric of my invention is composed 70 of a connected series of transverse rows of links formed of wire and one of which is indicated as 12 in Fig. 3. The links 12 all correspond with one another, and each link is of triangular outline and in one piece of 75 wire and formed with a base member 13 and converging side member 14, both of which at their outer meeting ends are formed with hooks 15. The base member 14 at its middle portion is formed with an outwardly projecting loop constituting an eye 16. The links 12 are all interengaged in the formation of the fabric, and the method of interengaging the links 12 is illustrated in Figs. 1 and 2. The hooks 15 of one transverse 80 series of links 12 are all engaged with the eyes 16 of the adjacent transverse series of links 12, and each link 12 of each transverse series of links has its side members 14 passed through the links at each side thereof so that 85 at the base ends of each side member 14 of each link said link becomes interlocked or interengaged with the base ends of the side members of the links at both sides thereof, whereby the links in one transverse series of 90 links become interlocked with each other, and the eyes 16 are interlocked with the hooks 15 of the links of the adjacent transverse series, this arrangement following 95 throughout the fabric and resulting in all 100 of the links 12 being interlocked with each other in transverse series and with the links in the adjacent transverse series.

It may be seen on reference to Fig. 1 that the links 12 are not only in transverse alinement, but also in longitudinal alinement, and that each link 12 in one transverse row is engaged at its hooks 15 with the eye 16 of the link immediately succeeding it longitudinally, and also that transversely con- 110

sidered the left hand side member 14 of each link is interlocked with the right hand side member of the link 12 at the left thereof, and that the right hand member 14 of each link is interlocked with the left hand side of the link at the right thereof. The side members 14 of each link being separable at their outer or hook ends 15 may be slipped through the adjacent links so that said side members may become, at their base ends, interengaged with side adjacent links. All of the links 12 are of triangular shape and hingedly connected together and have a high degree of efficiency in the formation of a spring fabric for a bedstead, said fabric being adapted to support the usual hair or other mattress provided for bedsteads. The row of links 12 at one end of the fabric are, by means of their hooks 15, connected with helical springs 17 of usual character which are connected with one end 10 of the main supporting frame, and the row of links 12 at the other end of the fabric have their eyes 16 connected with helical springs 18 of known character, which are hooked into holes formed in the other end 10 of the main carrying frame, as will be clearly understood on reference to Fig. 1.

The side edges of the main fabric composed of the links 12 must be sustained in a substantial manner, and in Figs. 1 and 2 I illustrate two different means for finishing off the edges of the fabric. In the construction shown in Fig. 1 I extend a stay rod, of wire or the like, 19 along through the left hand links 12 and connect the same by helical springs 20 with the end bars 10 of the rigid supporting frame, this rod 20 being interengaged with the angular adjoining portions of the outer sides 14 and base member 13 of the several links 12, and preferably at the intermediate points between each two transverse rows of links 12 I connect the rod 19 by short wire links 21 with a sheet metal longitudinal frame 22 of the character shown in my aforesaid application for Letters Patent, which frame 22 at its ends is connected by helical springs 23 with the end bars 10 of the main rigid supporting frame. The outer portion of the frame 22 is rounded and tubular and at its inner edges said frame is flat and apertured to receive the links 21.

In the construction shown in Fig. 2 I utilize the same rod 19 that I have shown in Fig. 1, but I connect said rod 19 by a series of links 24 with a corresponding rod 25 which extends lengthwise of the spring and is connected by helical springs 26 with the end bars 10 of the main supporting frame. In the construction shown in Fig. 2 I substitute the rod 25 for the frame 22 illustrated in Fig. 1, but otherwise the construction shown in Figs. 1 and 2 are alike.

65 The main features of my invention reside

in the series of triangular-shaped links 12 connected in transverse and longitudinal rows, as shown, in connection with the helical springs 17, 18 for the ends of the fabric and suitable stay rods or the like for the 70 side edges of the fabric. The links 12 admit of modification in outline, as indicated in Fig. 4, which illustrates a triangularly shaped link having sides 41 which are of greater length than the base member 40, the 75 link shown in Fig. 4 being otherwise the same as the links represented in Figs. 1, 2 and 3. The longer link, such as shown in Fig. 4, is a very desirable form of link and in some instances preferred over the equilateral form of link shown in Fig. 3.

What I claim as my invention and desire to secure by Letters Patent, is:

1. A bed-spring of the character described, comprising a rigid carrying frame, coiled springs connected with the end members thereof and a fabric connected with the inner ends of said springs, said fabric comprising transverse and longitudinal rows of links of triangular outline interengaged in series with one another at their sides in the transverse rows thereof, the base members of said links being formed with eyes, and the converging sides of said links having hooks engaging the eyes of the links in the 95 next adjacent transverse row of links.

2. A bed-spring of the character described, comprising a rigid carrying frame, coiled springs connected with the end members thereof, side-stays connected by outer of 100 said coiled springs with the end members of said frame, and a fabric connected with the inner ends of the other of said coiled springs and comprising transverse and longitudinal rows of links of triangular outline 105 interengaged in series with one another at their sides in the transverse rows thereof, the base members of said links being formed with eyes, and the converging sides of said links having hooks engaging the eyes of the 110 links in the next adjacent transverse row of links, said side-stays being threaded through the angular outer edges of the side links of said fabric.

3. A bed-spring of the character described, 115 comprising a rigid carrying frame, coiled springs connected with the end members thereof, plural parallel side-stays connected by the outer of said coiled springs with the end members of said frame and being linked 120 together, and a fabric connected with the inner ends of the other of said coiled springs and comprising transverse and longitudinal rows of links of triangular outline interengaged in series with one another at their 125 sides in the transverse rows thereof, the base members of said links being formed with eyes, and the converging sides of said links having hooks engaging the eyes of the links in the next adjacent transverse row of links, 130

one of said side-stays at each side of the fabric being threaded through the angular outer edges of the outer side links of said fabric.

4. A bed-spring of the character described, comprising a rigid carrying frame, coiled springs connected with the end members thereof, and a fabric connected with the inner ends of said springs, said fabric comprising transverse and longitudinal rows of corresponding links of triangular outline connected with one another in series in the transverse rows thereof at their angular base corners, the base members of said links being formed with eyes and the converging sides of said links having hooks engaging the eyes of the links in the next adjacent transverse row of links.
5. A bed-spring of the character described, comprising a rigid carrying frame, coiled springs connected with the end members thereof, side stays connected by outer of said coiled springs with the end members of said

frame, and a fabric connected with the inner ends of the other of said coiled springs and comprising transverse and longitudinal rows of corresponding links of triangular outline connected with one another in series in the transverse rows thereof at their angular base corners, the base members of said links being formed with eyes and the converging sides of said links having hooks engaging the eyes of the links in the next adjacent transverse row of links, and the side links of said fabric at their outer angular base corners being connected with said side stays.

Signed at New York city, in the county of New York and State of New York, this 4th day of October, A. D. 1917.

ABRAHAM S. MEADOFF.
